UNITED STATES PATENT OFFICE.

FREDERIC E. BAGER, OF KENOSHA, WISCONSIN, ASSIGNOR TO FREDERICK C. AUSTIN,
OF CHICAGO, ILLINOIS.

TRENCHING-MACHINE.

1,400,712.

Specification of Letters Patent. Patented Dec. 20, 1921.

Application filed April 23, 1917. Serial No. 163,822.

To all whom it may concern:

Be it known that I, FREDERIC E. BAGER, a citizen of the United States of America, and resident of Kenosha, Kenosha county, Wisconsin, have invented a certain new and useful Improvement in Trenching-Machines, of which the following is a specification.

My invention relates to excavators for making trenches, and more particularly to machines of that kind in which the digging apparatus is arranged at the rear end of the excavator, whereby a trench is cut in rear of the machine during the forward movement thereof along the surface of the ground in the direction desired for the trench.

In the operation of excavators of this character, it has been found to be difficult at times to keep the earth from falling into the trench behind the machine, and this is particularly the case when the excavator is working in sand or soft ground.

Generally stated, the object of my invention is to provide an improved construction and arrangement whereby the sides of the trench are caused to slope, when such is necessary or desirable, so that the earth does not slide into the trench behind the machine, the slope given the sides of the trench being sufficient to prevent the earth from caving in after the trench is made.

It is also an object to provide certain details and features of construction and combinations tending to increase the general efficiency and desirability of a trenching machine of this particular character.

To the foregoing and other useful ends, my invention consists in matters hereinafter set forth and claimed.

In the accompanying drawings:

Figure 1 is a side elevation of the rear portion of a trenching-machine, showing the digging-apparatus thereof equipped with side-cutters for sloping the sides of the trench, embodying the principles of my invention.

Fig. 2 is a cross-section of the trench, showing the manner in which the sides are sloped to prevent them from falling into the trench.

Fig. 3 is a rear elevation of the machine shown in Fig. 1, looking in a direction at right angles to the digging-beam.

Fig. 4 is a view similar to Fig. 1, showing another form of my invention.

Fig. 5 is a rear elevation of the machine shown in Fig. 4.

Fig. 6 is a cross-section of the trench made by the machine shown in Figs. 4 and 5.

As thus illustrated, referring to Figs. 1, 2 and 3, my invention comprises a body A suitably mounted on traction-devices B, whereby the machine is slowly propelled in a forward direction during the making of the trench. At its rear end, said body is provided with a transverse shaft C upon which is supported the depending digging-beam D, which latter extends downward into the trench. The sprocket-chains E are provided with digging-buckets e and supported upon the sprockets or rotary supporting-elements F and G mounted at the upper and lower ends of the digging-beam, the sprockets F being mounted on the shaft C, which latter is the driving-shaft as well as the pivot for the beam. Thus the buckets are operated to travel in front of the beam and downward in rear thereof, the rising buckets cutting the trench. Any suitable means can be employed for raising and lowering the beam, to vary the depth of the trench, or whereby the beam can be raised and held above ground when the machine is required to travel from one place to another. The excavated dirt is automatically discharged by the buckets at the upper end of the beam, and may be disposed of in any suitable or desired manner.

Upper and lower cross-heads H and N are arranged to slide upon the digging-beam D, in any suitable manner, and are rigidly connected together by the downwardly converging bars g, and by parallel bars I, and the cross-head H is connected by links i with the cranks J on the outer ends of the shaft C, whereby the structure provided by said cross-heads and bars is reciprocated up and down on the digging-beam during the operation of the buckets. These bars g are provided along their forward edges with saw-teeth K for cutting the earth, and the dirt thus torn away from the side of the trench is allowed to fall into the path of the rising buckets, so that it is scooped up and carried upward. The angle of the bars g is such that they give the sides of the trench the desired slope (see Fig. 2), as the machine travels forward. As the buckets extend a distance in advance of the saw-teeth K, it follows that the trench is first formed with vertical sides, and that the upper portions of these sides are then cut away to form the final or sloping sides of the trench.

When the machine is working in soft ground, such as sand, sloping of the sides of the trench will prevent the earth from caving in behind the machine. The side-cutters are, however, readily removable from the digging-apparatus, by removing the cross-heads H and N from the digging-beam, and any suitable provision can be made for this purpose. The bars g can be flexible, so that they will yield to some extent during their up-and-down movement against the sides of the trench.

In Figs. 4, 5 and 6, the construction is as follows: The converging bars L are similar to those previously described, and are provided with saw-teeth l, but in this case said bars are pivoted near their lower ends upon the transverse member M which is carried by the digging-beam. A transverse connection N extends between the upper ends of the bars L, and parallel bars n extend upward from the inner surfaces of the bars L and across the connection N, being secured by rivets O to said connection. The upper ends 25 of these bars n are connected by links P with the cranks p on the shaft C previously described. With this arrangement, the rotation of the shaft C causes the bars L to oscillate about the transverse axis provided by the pivots m on the ends of the cross-member M, and this tears down the earth at the opposite sides of the trench, causing the dirt to fall into the path of the rising buckets. The trench is, therefore, first formed with 30 vertical sides (see Fig. 6), and is then provided with sloping sides in rear of the digging-buckets.

The transverse shaft C, of course, is common to both the trench cutter and the trench widening and bank sloping devices, and

serves for the operation of, as well as to provide a, transverse axis about which said trench cutter and devices are supported to swing up and down.

What I claim as my invention is:—

1. In an excavator for cutting a trench in rear thereof, as the machine moves slowly forward, a tilting digging beam depending from the rear end of the machine, an endless series of digging-buckets arranged to travel up and down on said beam, so that the rising buckets cut the trench ahead of the beam and then descend behind the beam, auxiliary cutting means carried on said beam and having back and forth movement thereon to slope the sides of the trench by cutting away dirt which falls into the path of said buckets, and devices for operating said auxiliary cutting means as a unit on said beam. 45

2. The structure, as set forth in claim 1, in which said means include a pair of downwardly converging bars having saw-teeth thereon, and means to rigidly connect said bars together, said devices being adapted to operate said bars back and forth in unison 50 against the sides of the trench.

3. The structure, as set forth in claim 1, in which said devices are provided at the upper end of said beam for operating said means back and forth against the sides of 55 the trench.

4. The structure, as set forth in claim 1, in which a shaft is provided for pivoting the upper end of said beam, and devices including crank arms on said shaft to operate 60 said buckets and said means. 75

Signed by me at Chicago, Illinois, this 3rd day of April, 1917.

FREDERIC E. BAGER.
